The ornamental design for a safety light, as shown and described.

DESCRIPTION

FIG. 1 is a front top perspective view of a first embodiment of a safety light showing my new design;

FIG. 2 is a top plan view thereof;

FIG. 3 is a front elevation view thereof;

FIG. 4 is a left elevation view thereof;

FIG. 5 is a bottom plan view thereof;

FIG. 6 is a rear elevation view thereof;

FIG. 7 is a right elevation view thereof;

FIG. 8 is a front bottom perspective view thereof;

FIG. 9 is a front perspective view of a second embodiment of a safety light showing my new design;

FIG. 10 is a top plan view thereof;

FIG. 11 is a front elevation view thereof;

FIG. 12 is a left elevation view thereof;

FIG. 13 is a bottom plan view thereof;

FIG. 14 is a rear elevation view thereof;

FIG. 15 is a right elevation view thereof; and,

FIG. 16 is a front bottom perspective view thereof.

The broken lines depicting portions of a safety light for environment in the drawings are for illustrative purposes only, and form no part of the claimed design.
